UNITED STATES PATENT OFFICE.

LIVY D. MURPHY, OF BLUE SPRINGS, MISSOURI.

CAR-COUPING.

SPECIFICATION forming part of Letters Patent No. 371,618, dated October 18, 1887.

Application filed December 16, 1886. Serial No. 221,820. (No model.)

To all whom it may concern:

Be it known that I, LIVY D. MURPHY, of Blue Springs, Jackson county, State of Missouri, have invented certain new and useful 5 Improvements in Car-Couplings, of which the following is a full, clear, and exact description, reference being had to the accompanying drawings, forming a part hereof.

My invention relates to a car-coupling that 10 is provided with a swinging pin; and it may be said to consist in the devices and the combination and arrangement of devices herein-after set forth, and pointed out in the claims.

In the accompanying drawings, which illustrate the manner of carrying out the invention, Figure 1 is a perspective view of the end of a car having my improved coupling attached thereto. Fig. 2 is a longitudinal section through the draw-head, and showing the 20 swinging pin in its normal position before the link has been inserted. Fig. 3 is a similar section showing the pin in the act of engaging the link to make a coupling; and Fig. 4 is a detail view, enlarged, showing one edge of the 25 pin and the front side thereof, respectively.

Referring again to the drawings, the draw-head A is connected and attached to the car O in the usual manner; but the flared opening 10 for the link is made deeper than it is in 30 an ordinary coupling, to admit of an extra long link, such as C, being used, and it is provided with a projection, b, near its open end, which is engaged by the lower end of the pin B after a coupling has been made and after the strain 35 comes on the link. With this construction it is clear that a much shorter pin can be used, as in the absence of the projection b on the lower surface of the link-opening 10 a pin having sufficient length to reach down to the lower 40 surface of the outside of the draw-head would (to afford the necessary bearing-surface) have to be provided. As it is, the pin B can be made so short that its lower end need not project much below the plane of the lower surface of the link-opening, and thereby permit 45 of a very short slot, c, being provided in the under side of draw-head A.

Draw-head A is provided with a longitudinal slot, c, on its under side for the lower end 50 of the pin to swing in, and said slot extends through the wall of the draw-head and opens on the under surface thereof, which latter pro-

vision will allow all dirt or rubbish to drop out of the chamber 10. Said draw-head is also provided with a rectangular opening, c', 55 on its upper side, corresponding in size to the dimensions of the lower end of the pin B, and the rear side of this opening is inclined toward the rear end of the chamber 10, so as to permit the pin to be swung sufficiently far 60 back to make a coupling automatically, as shown more clearly in Figs. 2 and 3. This opening is made with two of its opposite sides somewhat longer than its remaining ones, thereby providing a hole that is somewhat oblong, so that the pin B, which is provided 65 with opposite projections at its lower end, can be inserted and fastened by revolving.

The projections 5 on opposite sides of the pin B are preferably formed integral with the 70 body of the pin, which may be done in any desired way, and the operation of fastening said pin in the draw-head is as follows: The lower end of the pin is first made to engage the opening c' while the projections 5 are in a 75 line that is longitudinal to the body of the draw-head—that is, the pin is turned sidewise, as shown in Fig. 4. Then, after the said projections have been inserted so far as to become 80 disengaged from the sides of the opening, the pin may be turned around about a half-revolution, when it cannot be withdrawn without turning sidewise again. The opening c' is also made with its front side inclined toward the link-opening, or rather beveled downwardly and forward, so as to allow the pin to be pulled a little forward when raised, so that 85 its lower end becomes disengaged from the projection b, thereby permitting said pin to be more easily withdrawn and disengaged from 90 the link in uncoupling when a strain is on the draw-head.

The pin B is made square at its lower end, and also at the point that is immediately below the shoulder 4, which rests upon the upper 95 surface of the draw-head when the pin is in a coupled position, and it is provided with a round portion intermediate of the two square portions for engaging the link without generating as much friction as would be generated 100 were the entire body of the pin rectangular in cross section. The number 12 indicates said round portion. The front side of the head of the pin B is provided with a recess, 13, which

is adapted to engage with the front upper corner of the opening c' when a coupling is being made, thereby permitting said pin to have more backward swing than it otherwise 5 would have and causing the coupling to be more certain of accomplishment.

Extending upward from the pin B and secured to its head by means of a ring, or in any desired way, is the pin-operating rod 3, the 10 upper end of which is provided with a suitable hand-piece, 1, and which is loosely secured to the end of the car O, so as to be raised a sufficient distance by the bearing-piece a or other suitable device. Cross-bars 2 are secured to the rod 3 at a convenient height thereon and extend out to each side of the car, so that the pin may be manipulated from the ground.

It will be observed that the link C is somewhat longer than links of the ordinary construction, and that it is provided with flat-surfaced ends. By this construction the link will reach farther back in the chamber 10 when the pin is in place, and its ends will therefore 25 be able to engage the upper surface of said chamber some distance back of the pin, and the link being thus fulcrumed at the front end of the chamber 10, and with its rear end engaging the upper surface of said chamber, it 30 should be obvious that the free end of the link will not drop down so far as it would if its ends were devoid of the flat surfaces or extensions before described, and that said free end would be more likely to enter the link- 35 opening of another draw-bar when a coupling was to be made. The number 14 represents said flat surfaces or extensions. The link C is also provided with curved recesses 15 at its ends, the purpose of which is to guide the end 40 of said link to a central position on the pin when the two come in contact in making a coupling. Of course these recesses may be V-shaped, if desired.

The operation of the invention may be described as follows: When the end of the link 45 C strikes the pin B when the latter is in the

position shown in Fig. 2, the lower end of the pin will be swung inward until it becomes disengaged from the link, and then gravity will cause it to swing back to its normal vertical 50 position, and the said link cannot then be withdrawn until the said pin is pulled upward.

If it be so desired, the ordinary link may be used with the car-coupling herein shown, 55 and the operation of the invention will not thereby be substantially departed from.

Having thus described my invention, what I claim is—

1. The draw-head A, provided with rectangular opening c' , corresponding in size to the lower end of the pin, in combination with the pin B, having opposite projections 5 on its lower end, for the purpose set forth.

2. In a car-coupler, the pin B, made square 65 at its lower end and at a point immediately below its head, and with a round portion located intermediate of the square portions, for the purpose substantially as described.

3. In a car-coupler, the combination of the 70 pin, the pin-operating rod 3, loosely connected to the head of the pin, and the cross-bars 2, rigidly secured to the said rod and extending toward the respective sides of the car, substantially as herein described.

4. In a car-coupler, the combination of the 75 pin, the pin-operating rod 3, loosely connected to the head of the pin and extending upward within reach from the top of the car and loosely secured to the end of the car in a vertical position, a suitable bearing for the upper end of said rod located on the end of the car, and cross-bars 2, rigidly secured to said rod and extending toward the respective sides of the car, substantially as described.

In testimony whereof I affix my signature in presence of two witnesses.

LIVY D. MURPHY.
